UNITED STATES PATENT OFFICE.

ALPHEUS W. ALTORFER, OF PEORIA, ILLINOIS, ASSIGNEE TO ALTORFER BROS. COMPANY, OF EAST PEORIA, ILLINOIS, A CORPORATION OF ILLINOIS.

WRINGER.

Application filed April 23, 1923. Serial No. 634,149.

To all whom it may concern:

Be it known that I, ALPHEUS W. ALTORFER, a citizen of the United States, a resident of Peoria, in the county of Peoria and 5 State of Illinois, have invented new and useful Improvements in Wringer, of which the following is a specification.

This invention has reference to wringers, and it has for its principal object to provide 10 a quick releasing means for the compression on the wringer rolls in the event of a person accidentally getting the fingers or hand caught between the rolls, or in the event of fine fabrics becoming entangled.

15 The invention has for a further object to improve the construction of the wringer frame, and including therein the improved releasing means for the wringer rolls.

That the invention may be more fully 20 understood reference is had to the accompanying drawings forming a part of the description, which illustrates a preferred embodiment of the invention, and in which:—

25 Figure 1 is a side elevation partly in section, showing a wringer embodying my invention;

Figure 2 is an end view of Figure 1; 30 Figure 3 is a view similar to Figure 1, except that the releasing means has been operated to release the compression on the wringer rolls;

Figure 4 is a cross-section as the same 35 would appear if taken on the line 4—4 Figure 3;

Figure 5 is a cross-section as the same 40 would appear if taken on the line 5—5 Figure 3; and

Figure 6 is a cross-section as the same 45 would appear, if taken on the line 6—6 Figure 3.

Like characters of reference denote corresponding parts throughout the figures.

The frame of the wringer includes the 50 duplicate sections 1, 1 preferably made of metal, although they could be made of other material. Said sections are formed at their opposite ends with the upstanding and matching semi-spherical bodies 2, 2 which 55 when the said sections are joined or secured together form barrels which encase the compressing means for yieldingly holding the wringer rollers in coacting relation. Said barrels have preferably open upper ends and closed lower ends, as shown. At one end of

the frame housing extensions 3, 3 are provided, which, together enclose the gears for the rollers. The barrels of the wringer frame are connected by the reach members 4, 4 and 5, 5 which unite in a central body 60 or frame part 6, 6 and the reach members 7, 7.

The driving and driven wringer rolls are designated 8 and 9 respectively. The roller 8 having a shaft extension 10 which passes 65 out of the wringer frame and into a gear casing 11 which encases gearing not shown, for operating said shaft from a suitable source of power. The two rolls 8 and 9 have shaft extensions 12 and 13 respectively, 70 journaled in the housing 3 and carry the intermeshing gear wheels 14 and 15. The roller 9 has a shaft extension 16 journaled in that end of the frame carrying the shaft 75 10 of the roller 8.

In each barrel of the frame bearing blocks 17 and 18 are provided for the shaft extensions of the rollers 8 and 9 and in juxtaposition to each block 18 is a plate 19 formed or provided with a stud 20, and bearing 80 against each plate 19 and encircling its stud 20 is a coil spring 21, which also assumes an upstanding position in the barrel, and the upper ends of said springs also encircle studs 22 on plates 23 similar to the 85 plates 19. Said plates 23 and approximately the upper half portions of the springs 21 are carried in inverted cup-like sleeves 24 carried in the upper ends of said barrels. Having a threaded connection with the upper closed ends of said sleeves 24 are thumbscrews 25 which engage with the plates 23 for the purpose of adjusting the position 90 of the plates 23 and increasing or decreasing the tension in the springs 21. The barrels at their upper ends are chambered, as at 26 to receive a flange 27 on the lower ends of the sleeves 24, and also coil springs 28 which normally rest on said flanges 27, and act as a cushion in a manner to be explained. 100

The sections of the wringer frame are joined when placed together by means of bolts 29 passing through the walls of the barrels and between the shaft extension of the rollers 8 and 9; also by a bolt 30 passing 105 through the central body or frame part 6, and by short pins or spindles 31 passing through reach members 4, 4 which serve as fulcrum pins or members for levers to be described. The sections of the frame part 110

6 are formed or provided with the upstanding matching ears 32, to which has a pivotal connection a lever to be described.

- 33, 33 designate a pair of similarly constructed levers which are fulcrumed on the pins or spindles 31. The short arms 34 of said levers normally overlie and bear down against the upper closed end of the sleeves 24 in the barrels of the wringer frame, while 10 the long arms 35 of said levers are lifted and held raised by the cam like shoulders 36, 36 on a lever 37 having a bifurcated end 38 which straddles and is pivoted to the ears 32 on the frame part 6. In the position of 15 the levers 33, 33 just stated, the cushion springs 28 rest idly on the flanges 27 of the sleeves 24, and only act to cushion the thrust of the sleeves 24, when the lever 37 is moved downwardly releasing the sleeves 24 permitting 20 the springs 21 to expand and relieve the pressure on the wringer roll 9.

While I have shown the gear casing 11 attached to the wringer, and wringer and casing swingable on a post or stand, no 25 claim is made in this application to such structure and the same, therefore, need not be further described or detailed.

Assuming now that the parts are in the relative positions shown in Figure 1 of the 30 drawing with the wringer roller surfaces in contact, compression being applied through the coil springs 21, and the person operating the wringer getting his or her fingers between the rollers, or fine fabrics 35 becoming entangled, such operator with the other hand will grasp the lever 37 drawing it down from the position shown in Figures 1 and 2 to the position shown in Figures 3 and 4. Such movement of the lever 37 40 moves the cam like shoulders 36 from beneath the long ends 35 of the levers 33 permitting the coil springs 21 to expand forcing upwardly the sleeves 24 which will release the tension and pressure on the roller 9, that it may be lifted away from the roller 8, see Figure 3. As the levers 33 are oscillated under pressure of the springs 21 the short ends 34 of said levers move out of the path of the sleeves 24 but not out of the path 45 of the cushion springs 28, which are lifted by the flanges 27 on the sleeves 24 when the latter are raised, and said springs 28 engage with the short ends 34 of the levers 33 stopping the upward movement of the sleeves 50 55 24, in a cushion like manner and without jar.

To return the parts to their normal operative positions the sleeves 24 are again depressed to a position which will permit the 60 levers 33 to again engage the same upon the raising of the lever 37, which, as it is raised, will cause its cam like shoulders 36 to ride under and hold the long ends 35 of the levers 33 raised, as in Figures 1 and 2. To 65 relieve the tension in the springs 21 the

thumb-screws 25 may be unscrewed; likewise screwing them down will increase the tension.

What I claim is:—

1. In a wringer, in combination, a frame 70 having upstanding barrels at each end, wringer rolls journaled in said frame, springs in said barrels coacting with said rolls, means in the barrels to compress said springs, means to release the compressing 75 means and cushion springs in the barrels adapted to act upon the release of said compressing means.

2. In a wringer, in combination, a wringer frame, wringer rolls journaled in said frame, springs coacting with said rolls, means for compressing said springs, a lever coacting with each spring and fulcrumed on said frame, and a lever for controlling said two first mentioned levers also fulcrumed on 80 said frame, said controlling lever laterally swingable with its controlling end riding under ends of said first mentioned levers.

3. In a wringer, in combination, a wringer frame, wringer rolls journaled in said frame, springs coacting with said rolls, means for compressing said springs, a lever coacting with each spring and fulcrumed on said frame, a lever for controlling said two first mentioned levers also fulcrumed on 85 said frame, and cushioning means arranged to act on the release of said compressing means simultaneously with the actuation of said levers.

4. In a wringer, in combination, a wringer frame, wringer rolls journaled in said frame, springs coacting with said rolls, compression means for each spring including an inverted cup like sleeve to receive an end of the spring and a thumb-screw to coact with said spring, a pair of levers fulcrumed on said frame, each normally engaging one of said sleeves, and a lever for controlling said first two mentioned levers fulcrumed on said frame, said controlling lever laterally swingable with its controlling end riding under ends of said first mentioned levers.

5. In a wringer, in combination, a wringer frame having upstanding barrels at each end, wringer rolls journaled in said frame, coil springs in said barrels coacting with said rolls, inverted cup-like sleeves in said barrels associated with said springs, a lever to normally engage over each sleeve, and a lever to control the aforementioned levers.

6. In a wringer, in combination, a wringer frame having upstanding barrels at each end, wringer rolls journaled in said frame, coil springs in said barrels coacting with said rolls, bearing plates for each end of said springs, sleeve like members for the upper ends of said springs and enclosing the bearing plates for the upper ends of said springs, thumb screws having a threaded relation with said sleeves and adapted to 125 130

- bear against the encased bearing plates, levers fulcrumed on said frame and normally engaging over said sleeves, and a lever for controlling said aforementioned levers.
7. In a wringer, in combination, a wringer frame having upstanding barrels at each end, wringer rolls journaled in said frame, coil springs in said barrels coacting with said rolls, bearing plates for each end of said springs, sleeve like members for the upper ends of said springs and enclosing the bearing plates for the upper ends of said springs, thumb screws having a threaded relation with said sleeves and adapted to bear against the encased bearing plates, levers fulcrumed on said frame and normally engaging over said sleeves, a lever for controlling said aforementioned levers, and cushion springs adapted to coact with said levers and with the levers normally engaging the same.
8. In a wringer, in combination, a frame, wringer rolls journaled therein, compression means in the frame adapted to coact with said rolls, a pair of levers lying longitudinally of the frame and fulcrumed thereon, the outer ends of each lever adapted to coact with said compression means, a lever fulcrumed on said frame intermediate its ends and having cam-like shoulders to ride under the inner ends of said aforementioned levers to control the same, and cushioning means associated with said compression means and adapted to contact with the outer ends of the first mentioned levers upon the release of the compression means.
9. In a wringer, in combination, a frame having upstanding barrels at its ends, each being provided with an off-set chamber, wringer rolls journaled in said frame, coil springs in said barrels, means to compress said springs including a member movable axially in said barrels, a pair of levers fulcrumed on said frame, each adapted to bear against one of said axially movable members, a lever for controlling said aforementioned levers, and cushion springs in the chambered portions of said barrels and between portions of said axially movable members and said first mentioned levers.

In witness whereof, I have hereunto affixed my hand this 18th day of April, 1923.

ALPHEUS W. ALTORFER.
